UNITED STATES PATENT OFFICE.

WILLIAM F. BISHOP, OF WASHINGTON, DISTRICT OF COLUMBIA.

VALVE-STEM BASE OR PAD.

1,363,386.

Specification of Letters Patent. Patented Dec. 28, 1920.

Application filed May 3, 1916. Serial No. 95,210.

To all whom it may concern:

Be it known that I, WILLIAM F. BISHOP, a citizen of the United States, residing at Washington, District of Columbia, have invented certain new and useful Improvements in Valve-Stem Bases or Pads, of which the following is a specification.

This invention relates to the pads employed as the base for the valve stems of pneumatic tires, and, while designed with special reference to use with the inner tubes of double tube tires, it is obviously applicable to other structures adapted to be inflated through the well known valve stems.

15 In the manufacture of the inner tubes of pneumatic tires it is customary to reinforce the pure rubber of the inner tube at the point apertured for the reception of the valve stem by what is known as a "pad" (usually formed, in part at least, of fabric) cemented either to the inner or outer surface of the tube, and to then insert the valve stem from the inside of the tube through a circular aperture cut through the associated 25 tube and pad, and then apply the washer and clamp nut on the exterior of the tube.

It has been proposed to embed within the thickness of an inner tube one or more thicknesses of fabric provided with a slit or elliptical orifice arranged longitudinally of the tube, to the end that the head or button of a valve stem may be inserted from the exterior of the tube.

The object of my invention is to provide 35 an air containing body, such as the inner tube of a tire, with a "pad" which will permit of the insertion of the head of the valve stem from the exterior of the tube and insure against lateral expansion or stretch of the tube adjacent the valve stem orifice while 40 permitting limited expansion or stretch in the direction of the circumferential line of the tube adjacent said orifice.

A further object of the invention is to 45 embed or incorporate within the thickness of the wall of an inner tube a "pad" of multiple construction which, while permitting limited expansion or stretch of the tube lengthwise of the tube, will prevent expansion thereof laterally.

With these and minor objects in view, my invention consists in a pad or valve-stem base of multi-ply construction adapted to yield or elongate in one direction and prevent yield in a direction at right angles

thereto. It further consists in an inner tube for tires provided with a multi-ply pad permitting yield or stretch circumferentially, but preventing yield transversely. It further consists in an inner tube for tires having incorporated between its exposed surfaces a multi-ply pad designed to yield or stretch circumferentially of the tube, but to prevent yield or stretch transversely thereof.

60 In the accompanying drawing illustrating embodiments of my invention:

Figure 1 is a plan view of a short section of an inner tube provided with my improved tube base, certain parts being broken away 65 to show the relation of parts concealed in a complete tube.

Fig. 2 is a similar view, the tube base being shown as apertured to permit the insertion of the head of the valve stem.

Fig. 3 is a longitudinal section taken on the line A—B of Fig. 1.

Fig. 4 is a transverse section of the tube, showing the valve stem and its adjuncts in operative position.

Fig. 5 is a plan view of a stem base having additional plies for a heavier tube, parts broken away to show relative positions of underlying parts.

Fig. 6 is a plan view looking at the opposite side of the valve-stem base or pad constructed as in Fig. 5.

Fig. 7 is an edge view of my valve-stem base or pad shown in Figs. 5 and 6.

Fig. 8 is a plan view of the pad looking 90 at the side opposite that shown in Fig. 1.

The same reference characters are used in the several figures to designate identical parts.

My valve-stem base or pad, as a whole, 95 when used with an inner tube, is preferably oval in contour and is of multiple-ply construction, the plies being of greater or less number to suit the pressure or weight adapted for the diameter of the tire with which it 100 is to be used or the inner tube to which it is to be applied or to be embodied as an integral part, and the aperture therethrough for the valve stem will be of such diameter as to snugly fit the reduced part of the valve stem 105 adjacent the head.

In speaking of the process of making my pads it will be understood that before vulcanization the lightest pad consists of two plies of fabric and an interposed ply of 110

unvulcanized rubber, but after vulcanization the rubber ply will be incorporated with the fabric, thus constituting a two-ply pad.

- This valve-stem base or pad, referring to 5 Figs. 1 to 4, prior to vulcanization is of three-ply construction and comprises a preferably oval blank of unvulcanized sheet rubber 1 provided on one side with two similar semi-oval patches 2 and 3 of "frictioned" or 10 "rubberized" fabric, the adjacent edges 4 of which are parallel, but with a space between substantially equal to the diameter of the reduced part 5 of the valve stem 6 adjacent to the head 7 thereof, as shown in Fig. 4.
- 15 In constructing these patches 2 and 3 they may be cut to proper form and size by an oval die which will cut the pair of patches, or an oval of proper size may be marked on a fabric, the major axis of the oval being 20 bias or diagonal to the weft and warp threads, and then an oval blank is severed from its web and the blank be then severed on its major axis or longitudinal center, and the two patches 2 and 3 of fabric laid upon 25 a sheet or blank 1 of unvulcanized rubber with the severed edges 4 parallel and spaced apart a distance substantially equal to the diameter of the reduced part 5 of the valve stem 6 adjacent the head 7.
- 30 The patches 8 and 9 are formed from the same fabric, the longer axis of the oval being, in this case, parallel with one set of threads and at right angles to the other set, and these patches are severed laterally on 35 the minor axis of the oval and the parts laid on that side of the rubber blank 1 opposite the patches 2 and 3 with their parallel edges spaced apart, as in Fig. 8.

The positions of the two pairs of patches 40 with relation to each other, and the pad with relation to the tube, are well illustrated in Fig. 2.

The spaces between the parallel edges of the patches 2 and 3 and 8 and 9 will be filled 45 with strips 10 of unvulcanized rubber of a thickness equal to that of the fabric in order to form a continuous surface for contact with the usual washer 11 defining the limit of the valve stem and the opposing surface 50 of the head or button 7 of the valve stem.

A strip 10 of unvulcanized rubber is placed between the edges of the two patches 2-3 and 8 and 9 of fabric of each layer and the strips of each of the two layers are at a 55 right angle to the strip of the other layer. The fabric of the layer of patches 8 and 9 which has its intervening strip at right angles or transverse to the direction of the travel of the tire is cut straight, while that 60 of the layers 2 and 3 having the intervening strip in the direction of the travel of the tire is cut bias or diagonal.

This is of importance as not only rendering a close contact adjacent the reduced portion or base of the valve stem, but in con-

nexion with the intervening strips of unvulcanized rubber will prevent air holes of the pad while being rolled in embodying or connecting it with the tube or blistering in vulcanization.

The pad or stem base so far described is designed for employment with inner tubes of tires of the smaller diameters used on wheels for the lighter types of motor cars and the like. For heavier tires I increase 75 the thickness of the pad, as in Figs. 5, 6 and 7, by the addition of one or more pairs of patches constructed in all respects like those heretofore described except for the addition of other thicknesses; as, for instance, as 80 shown in the longitudinal section, Fig. 7, the uppermost patches may be of fabric with the threads arranged straight with relation to the circumference of the tire; that is to say, one series of threads will be parallel 85 with the major axis of the oval and the other series parallel with the minor axis thereof so that there can be no stretch of the fabric either longitudinally or transversely, though the filling strips 10 and interposed rubber 90 sheet 1, which are integral after vulcanization, will permit limited stretch of the pad, as a whole, longitudinally. The next lower thickness will be of unvulcanized rubber, and the next below will be of fabric, the 95 weft and warp threads of which will be diagonal to the parallel edges 4.

As the opposing edges of the patches 2 and 3 and the patches 8 and 9 will fit snugly against the reduced part 5 of the valve stem, 100 and the filler strips 10 will maintain the continuity of surface of a given layer or thickness of the pad, it is apparent that there will be no tendency of leak at this junction of the valve stem and the valve-stem aperture 105 of the tube; and, moreover, the opposing surfaces of the valve stem head and the washer will have an even surface to clamp between them.

I claim:

1. A base or pad for the valve stem of pneumatic tires and the like, consisting of superposed pairs of spaced apart fabric patches with interposed rubber, the weft and woof threads of one pair of patches being 115 arranged diagonally with relation to another pair of patches, and the spaces between the parallel edges of the respective pairs of patches crossing at right angles.

2. The combination with the air tube of a 120 pneumatic tire or the like, of an embedded pad consisting of superposed pairs of spaced apart fabric patches with interposed rubber having the threads of one pair arranged diagonally with relation to another pair, and the rubber filled spaces between the respective pairs crossing at right angles.

3. An air tube for pneumatic tires provided with an integral valve-stem pad comprising pairs of fabric patches spaced apart, 130

the threads of said patches being diagonal to the circumferential line of the tube, and pairs of spaced apart fabric patches, the threads of which are parallel and transverse 5 to the circumferential line of the tube, and unvulcanized rubber interposed between said pairs of patches.

4. An inflatable tube or the like provided with a valve pad consisting of a plurality 10 of superposed layers of fabric with an intervening layer of rubber, each of said fabric layers being formed of two separated fabric patches with an intervening rubber strip extending along the entire separated 15 lengths of said patches, and the patches of one of said fabric layers being cut bias or diagonal, while that of the other is cut straight, substantially as described.

5. An inflatable tire tube or the like provided with a valve pad consisting of a plurality 20 of superposed layers of fabric with an intervening layer of rubber, each of said fabric layers being formed of a pair of patches separated along their entire lengths 25 and provided with an intervening strip of rubber, substantially as described.

6. A tube for a tire carrying a plurality 30 of fabric layers with an intervening layer of rubber, said fabric layers being each formed of a pair of separated patches of fabric with an intervening strip of rubber, the rubber strip of one fabric being at right angles to that of the other fabric layer and the fabric of the layer having its strip trans- 35 verse to the travel of the tire being cut straight, while that of another layer is cut diagonal or bias, substantially as described.

7. A tube for a tire having embedded therein a pad consisting of a plurality 40 of layers of fabric with an intervening layer of rubber, each of said layers of fabric being formed of a pair of separated patches, the material of one of which is cut bias and the material of the other cut straight and 45 said patches having between them a strip of rubber, substantially as described.

8. A tube for a tire carrying a pad consisting of a plurality of layers of fabric with an intervening layer of rubber, each of said layers of fabric being formed of patches 50 separated along their entire lengths by intervening strips of rubber, substantially as described.

9. A tube for a tire carrying a pad consisting of a plurality of layers of fabric and 55 an intervening layer of rubber, the fabric layers each being formed of a pair of separated fabric patches with an intervening strip of rubber and the rubber strip of one of said fabric layers being at a right angle 60 to the strip of another fabric layer, substantially as described.

10. A tube for pneumatic tires having a reinforced pad embedded therein, said pad consisting of a plurality of layers of material, each layer being formed of two pieces of non-elastic fabric separated from each other along their entire lengths and having a filling piece in the intervening space; the filling pieces of the said layers being of 70 rubber and arranged at right angles to each other, the fabric of one of the layers, that having its filling piece which extends in the direction of the travel of the tube, cut bias, while the fabric of the other layer is cut 75 straight, substantially as described.

11. A tube for pneumatic tires carrying a valve-stem pad comprising patches of fabric separated from each other along their entire lengths with filling strips of rubber, 80 substantially as described.

12. A tube for pneumatic tires, having an opening therethrough, and a plurality of superposed staggered strips vulcanized in the body thereof, the inner edges of said 85 strips being adjacent to the opening, whereby when the head of a valve stem is inserted through the opening the rubber will expand and permit the strips of material to move relatively to one another.

In testimony whereof I affix my signature.

WILLIAM F. BISHOP.
